UNITED STATES PATENT OFFICE.

CHARLES SEAMAN, OF NEW YORK, N. Y., ASSIGNOR OF ONE-HALF TO MOSES LOEWENTHAL, OF BROOKLYN, NEW YORK.

DRIVING-MECHANISM GUARD.

1,116,134.

Specification of Letters Patent.

Patented Nov. 3, 1914.

Application filed November 12, 1913. Serial No. 800,887.

To all whom it may concern:

Be it known that I, CHARLES SEAMAN, a citizen of the United States, residing at the borought of Brooklyn, city of New York, 5 in the county of Kings and State of New York, have invented certain new and useful Improvements in Driving-Mechanism Guards, of which the following is a specification, reference being had therein to the accompanying drawings, forming part thereof.

My invention relates to guard devices and is, more particularly, a guard for the driving mechanism of power-driven sewing machines.

An important object of my invention is the protection of the operators and others from injury.

Another object is to protect the work or material being sewed and the clothing of the operator from soiling.

Other objects and advantages of my invention will hereinafter appear.

Heretofore a narrow board or bar, called a "skirt guard," has been placed across the machine a slight distance above the floor rearwardly from the treadle and the feet of the operator and forwardly of the power shaft or drive shaft of the machine. The skirt guards are very ineffective at best, 30 and are frequently out of place. Moreover, should an operator drop an article on the floor, in bending over or stooping to pick it up, there is serious danger of her hair becoming entangled with some part of the driving mechanism, and such accidents have resulted in severe injury. Sometimes a transmission belt will break and the loose end, striking the operator, will give her a sudden fright, causing her to lose control of

40 the machine, the usual result being that the needle pierces her finger. Also sometimes a piece-work operator will throw off the transmission belt with her foot, claiming it has dropped off, with the object of having the belt tightened so as to get more speed out of her machine. Also in rebelling, the adjuster, if a novice, will invariably place his arm over the shaft, and this is very dangerous. It has also been the common practice heretofore to attach a cloth apron to the front of the machine, thereby to protect the work and the clothing of the operator to some extent from oil and grease, but these aprons themselves quickly become

soiled, and are neither effective nor sanitary. Operators, in an effort to protect the work from oil and grease, usually lay the work across the top of the work box, which for that purpose is pushed unduly near the machine and is often pushed against the transmission mechanism. Furthermore, many machines are equipped with a knee-lift, and the cloth apron has proved a great inconvenience in the operation of such machines.

65 The guard device of my invention takes the place of and far more effectively performs the functions of both the usual skirt guard and the usual apron and also performs important additional functions, in fact it effectively remedies and removes all the dangers and objections of the hereinbefore noted heretofore common practice.

70 My invention includes a plurality of guard sections hinged together and adapted to be arranged so as to extend beneath the machine table in the space between the machine table and the floor and interposed between the operator and the driving mechanism of the machine, the guard sections being both separately and collectively foldable for access to the parts of the machine and being detachably held in place at the guarding or protective position by disconnectible means.

75 80 85 My invention more particularly includes features of construction and combinations of parts as will appear from the following description.

I shall now describe the guard device embodying my invention illustrated in the accompanying drawings and shall thereafter point out my invention in claims.

90 95 100 105 Figure 1 is a front elevation of a sewing machine equipped with the guard of my invention. Fig. 2 is a vertical section on a plane indicated by the line 2-2 of Fig. 1 as viewed from the right. Fig. 3 is a similar view indicated by line 3-3 of Fig. 1, parts of the machine being omitted and the folded position of the guard being indicated by broken lines. Fig. 4 is a horizontal section on a plane indicated by the line 4-4 of Fig. 1 as viewed from above, parts of the machine being omitted. Fig. 5 is a perspective of the guard device unattached to a machine.

The accompanying drawings are directed

more particularly to the guard device of my invention, but, for the purposes of better illustration and for a proper understanding of the invention, the principal parts of a power-driven factory sewing machine of a usual construction are also shown. The complete guard device of my invention, as illustrated in the drawings, may be made entirely of metal and japanned. The guard 10 illustrated in the drawings includes four sheet metal guard sections hinged together. A lower guard section 1 inclines slightly forward and is rigidly supported in this position with its lower edge spaced a few 15 inches from the floor, by means of angular supporting legs 2, shown as two in number, one leg adjacent to each end of the guard section. The guard section 1 may be secured to the legs 2 by means of rivets as 20 shown, and the legs 2 are shown as fastened to the floor by means of screws. The lower rigidly supported guard section 1 extends from near the frame of the machine at the left of the machine to a point adjacent to 25 the treadle-rod of the machine, as appears in Fig. 1, and is located rearward of the treadle and forward of the drive shaft of the machine (Figs. 1, 2 and 4), shown as provided with the usual belt pulleys, etc.

30 A main or middle guard section 3 is of the same length as and coterminous with the lower guard section 1 and is hinged at its lower edge to the upper edge of the lower guard section, by means of hinges 4. The 35 middle guard section 3 is wider than the lower guard section 1 and, in the protective position, extends in a vertical position well up toward the table of the machine beneath the table, but clearing the machine parts, 40 such as the usual box or drawer, as clearly appears in Fig. 1. Disconnectible means for detachably holding this middle guard section in the upright or protective position are provided. A supporting bar 5 is rigidly 45 secured, as by rivets as indicated, to the middle guard section 3 at near the middle of its length and projects beyond or above the upper edge of this guard section and is of a length to just clear the lower surface 50 of the machine table, as most clearly appears in Fig. 3. The upper end of the bar 5 is provided with a latch 6, shown as of a usual construction, a keeper 7 for the latch being attached to the lower side of the 55 table. By disengaging the bolt of the latch 6 from the keeper 7, the middle or main guard section 3 may be folded forward and downward to the position indicated by 60 broken lines in Fig. 3.

65 A smaller upper guard section 8 is hinged at its lower edge to the upper edge of the middle guard section 3, by means of hinges 9. The upper guard section 8 extends in length from midway of the middle guard section 3 to the end thereof at the

right as seen from the front (Figs. 1, 4 and 5). In its protective position, the upper guard section 8 extends from the upper edge of the middle guard section 3 upward and forward at substantially an angle of 70 forty-five degrees and terminates at the lower surface of the table of the machine near the front edge thereof, and may be detachably held at this position by means of a disconnectible device shown as a screw-eye 75 10 entering the material of the table from below and forming a button. The upper guard section 8 is opposite the shuttle mechanism of the machine, and the upper corner at the right of this guard section is 80 shown as cut away or notched, so as to clear projecting parts of the machine in folding, such as the knee-lift device appearing in Fig. 1. By turning the button 10, the upper section 8 may be folded downward relatively to the middle section 3, or it may be folded down with and beneath the middle section, as indicated by broken lines in Fig. 3.

85 A lateral guard section 11 is hinged at one of its ends to the adjacent end of the middle guard section 3 at the right, as viewed from the front of the machine, by means of hinges 12, and may swing horizontally on these hinges and also may fold 90 downward with the middle section 3. The lateral guard section 11 is of generally curved shape, having two plane vertical portions at right angles to each other and joined by an intermediate bent or curved 95 portion. In the protective position, the lateral guard section 11 extends first forward from the middle guard section 3 at right angles thereto and then, through the curved portion, extends laterally parallel 100 with the middle guard section 3. The forward portion of the lateral guard section 11 extends up to the lower side of the table, but the rear portion is cut away at the top, so as, in folding horizontally, to clear the 105 upper guard section 8 and projecting parts of the machine, such as the knee-lift device (Fig. 1). The lateral guard section 11 may be detachably held at the protective position by disconnectible means, shown as a 110 hook 13 pivoted on this guard section adjacent to its upper edge and engageable with a small eye 14 shown as carried by the sewing machine table at its under side (Figs. 1 and 2). The lateral guard section 11 in its 115 protective position is located both at the side of and forward of the transmission mechanism of the machine, including the usual belted cone pulley, as clearly appears 120 from Figs. 1, 2 and 4 of the drawings.

125 It will be seen, as perhaps most clearly appears in Fig. 5, that my invention provides a unitary device which may be readily separately manufactured and installed on power-driven factory sewing machines, as 130

shown in the other figures of the drawings. The upper guard section 8 may be readily dropped down alone to gain access to the shuttle mechanism. The lateral guard section 11 may be turned on its hinges horizontally, like a door, to gain access to the transmission mechanism. To render the driving shaft and its adjuncts, at the back of the machine, accessible, the main or middle 10 guard section 3 is let down, together with the upper guard section 8 and the lateral guard section 11, the entire driving mechanism of the machine then being accessible, the upper guard section 8 folding under the 15 middle guard section 3 out of the way, as appears in broken lines in Fig. 3.

When the several sections of the guard device are fastened at the protective position, no part of the operator's person or 20 clothing can come into contact with any part of the driving mechanism, as clearly appears from the drawings, particularly Fig. 1, and all danger from this source is eliminated. Moreover, oil and grease from 25 no part of the machine, such as from the shuttle mechanism, from the transmission mechanism, or from the driving shafting, can reach either the work or the clothing of the operator.

30 It is obvious that various modifications may be made in the construction shown in the drawings and above particularly described within the principle and scope of my invention.

35 I claim:

1. A driving mechanism guard for power-driven sewing machines, comprising, in combination, a plurality of guard sections hinged together, including a rigidly supported lower guard section, a downwardly foldable middle guard section hinged at its lower edge to the upper edge of the lower guard section, disconnectible means for detachably holding the middle guard section at 40 the protective position, a downwardly foldable upper guard section hinged to the upper edge of the middle guard section and foldable downward relatively thereto and also therewith, and disconnectible means for detachably holding the upper guard section at the protective position.

2. A driving mechanism guard for power-driven sewing machines, comprising, in combination, a plurality of guard sections hinged together, including a rigidly supported lower guard section, a downwardly foldable main guard section hinged at its lower edge to the upper edge of the lower guard section, disconnectible means for detachably holding the main guard section at the protective position, a horizontally foldable lateral guard section hinged at one of its ends to one of the ends of the main guard section and foldable both horizontally rela-

tively thereto and downward therewith, and 65 disconnectible means for detachably holding the lateral guard section at the protective position.

3. A driving mechanism guard for power-driven sewing machines, comprising, in combination, a plurality of guard sections hinged together, including a rigidly supported lower guard section, a downwardly foldable middle guard section hinged at its lower edge to the upper edge of the lower 70 guard section, disconnectible means for detachably holding the middle guard section at the protective position, a downwardly foldable upper guard section hinged to the upper edge of the middle guard section and 75 foldable downward relatively thereto and also therewith, disconnectible means for detachably holding the upper guard section at the protective position, a horizontally foldable lateral guard section hinged at one of its ends to one of the ends of the middle guard section and foldable both horizontally relatively thereto and downward therewith, and disconnectible means for detachably holding the lateral guard section at the protective position.

4. A driving mechanism guard for power-driven sewing machines, comprising, in combination, a plurality of guard sections hinged together, including a main guard section 80 pivotally supported along its lower edge to fold downward, disconnectible means for detachably holding the main guard section at the protective position, a downwardly foldable upper guard section hinged to the upper edge of the main guard section 85 and foldable downward relatively thereto and also therewith, and disconnectible means for detachably holding the upper guard section at the protective position.

5. A driving mechanism guard for power-driven sewing machines, comprising, in combination, a plurality of guard sections hinged together, including a main guard section 90 pivotally supported along its lower edge to fold downward, disconnectible means for detachably holding the main guard section at the protective position, a horizontally foldable lateral guard section hinged at one of its ends to one of the ends of the main guard section 100 and foldable both horizontally relatively thereto and downwardly therewith, and disconnectible means for detachably holding the lateral guard section at the protective position.

6. A driving mechanism guard for power-driven sewing machines, comprising, in combination, a plurality of guard sections hinged together, including a main guard section 110 pivotally supported along its lower edge to fold downward, disconnectible means for detachably holding the main guard section at the protective position, a downwardly fold-

able upper guard section hinged to the upper edge of the main guard section and foldable downward relatively thereto and also therewith, disconnectible means for detachably holding the upper guard section at the protective position, a horizontally foldable lateral guard section hinged at one of its ends to one of the ends of the main guard section and foldable both horizontally relatively thereto and downwardly therewith, and disconnectible means for detachably holding the lateral guard section at the protective position.

7. A driving mechanism guard for power-driven sewing machines, comprising, in combination, a lower guard section, means for rigidly supporting the lower guard section in a forwardly inclined position, a middle guard section hinged at its lower edge to the upper edge of the lower guard section, disconnectible means for detachably supporting the middle guard section in substantially vertical position, an upper guard section hinged at its lower edge to the upper edge of the middle guard section, disconnectible means for detachably supporting the upper guard section in a forwardly inclined position, a forwardly and laterally extending curved lateral guard section hinged at one of its ends to one of the ends of the middle guard section to swing in substantially horizontal planes, and disconnectible means for

detachably holding the lateral guard section at the extended position.

8. A driving mechanism guard for power-driven sewing machines, comprising, in combination, a lower guard section, means for rigidly supporting the lower guard section, a main guard section hinged at its lower edge to the upper edge of the lower guard section, a supporting bar rigidly carried by and projecting upward beyond the upper edge of the main guard section, and a latch for holding the upper end of the bar thereby to hold the main guard section at the protective position.

9. A driving mechanism guard for power-driven sewing machines, comprising, in combination, a middle and an upper and a lower guard section all hinged together to fold, a lateral guard section hinged to the middle guard section, and separate disconnectible holding devices for the middle and upper and lateral guard sections, respectively, for holding each of such guard sections at the protective position.

In testimony whereof I have affixed my signature in presence of two witnesses.

CHARLES SEAMAN.
